UNITED STATES PATENT OFFICE.

DAVID REISZ, OF CLEVELAND, OHIO.

GAME APPARATUS.

Application filed May 8, 1925. Serial No. 28,879.

To all whom it may concern:

Be it known that I, DAVID REISZ, a citizen of the United States, and a resident of Cleveland, in the county of Cuyahoga and State of Ohio, have invented a new and Improved Game Apparatus, of which the following is a full, clear, and exact description.

This invention relates to game apparatus and more particularly to game apparatus, the broad concept of which is disclosed in my pending applications, one of which was filed July 17, 1922, Serial No. 575,532, and the other filed February 12, 1923, and given Serial No. 618,634.

An object of the invention is to provide a folding game board and game pieces with an improved framing mechanism which not only functions as a frame or partial enclosure for the game pieces but also serves to hold the game pieces on the game board so that when the framing device is moved or removed the pieces will be on the game board and can be conveniently positioned for play.

A further object is to provide a game apparatus including a game board having a pair of parallel fold lines spaced apart a distance approximating the thickness of the framing device and the game pieces, whereby when the framing device is located on a section of the game board with the game pieces in the framing device the other section of the game board can be neatly and smoothly folded so that two sections of the game board will lie flush with opposite faces of the framing device and function as a closure for the framing device to hold the game pieces in the framing device; and I may provide other additional means, as will hereinafter appear, to hold or secure the parts in such position.

With these and other objects in view, the invention consists in certain novel features of construction and combinations and arrangements of parts which will be more fully hereinafter described and pointed out in the claims.

In the accompanying drawings—

Figure 1 is a plan view, showing my improved game board and framing device separated;

Figure 2 is a perspective view, showing the several parts of the game apparatus assembled and enclosed within a sliding envelope;

Figure 3 is a view in section on the line 3—3 of Figure 2;

Figure 4 is a view similar to Figure 1, illustrating a modification;

Figure 5 is a view in transverse section of the game apparatus shown in Figure 4 when the latter is folded and the game pieces are in position therein;

Figure 6 is a fragmentary plan view similar to Figure 4, illustrating a modification;

Figure 7 is a view in transverse section through the completely closed and encased game apparatus, as shown in Figure 6, with the game pieces in position;

Figure 8 is a plan view, illustrating another modification;

Figure 9 is a view in section on the line 9—9 of Figure 8;

Figure 10 is a view in section, showing the game apparatus illustrated in Figures 8 and 9 when the apparatus is completely folded;

Figure 11 is a fragmentary plan view, illustrating another modification;

Figure 12 is a view in section, showing the game apparatus illustrated in Figure 11 when completely folded.

Referring more particularly to Figures 1, 2 and 3, 1 represents a game board, 2 a framing device, 3 game pieces and 4 an enclosing envelope. The game board may be made of any suitable material having the desired flexibility or rigidity in accordance with the desire of the trade. This board preferably has an ornamental surface such as the standard type of checker or chess board.

The board 1 is of rectangular form and is provided at opposite sides of a center line with a pair of parallel fold lines 5, 5. These fold lines 5, 5 are spaced apart a distance approximately the same or slightly greater than the thickness of the framing device 2.

The framing device 2 may be made of any suitable material, is of general oblong form, and provides a space or spaces therein sufficient to accommodate the proper number of game pieces 3.

It will be noted that the game pieces 3 are of approximately the same thickness or depth as the framing device, so that when the framing device is positioned on the game board with the game pieces therein, one section of the game board can be folded over the framing device and the game pieces, and the two sides or sections of the game board will provide flush closures for the opposite

sides of the framing device and completely encase the game pieces.

When the game board is opened, the framing device will hold the game pieces on the board, and when the framing device is moved or removed it will leave the game pieces on the respective player's half of the board for convenience in assembling to play the game.

10 To hold the parts in their folded or assembled form, I may provide a sliding envelope, such as is shown in Figure 4, which is of a size and shape to fit the assembled game apparatus and which is preferably made

15 with finger-receiving recesses 6 so that the game board can be easily grasped and removed from the envelope.

In the modification shown in Figures 4 and 5 I provide a game board 7 which is slightly wider at one-half than at the other, and form flanges 8 around both halves of the game board and at right angles to the game board and of a proper depth, so that when the framing device 2 and the game pieces 3 are located on the board the board can be folded and the flanges 8 will provide a snug closure and hold the parts assembled.

In the form of my device illustrated in Figures 6 and 7, a foldable extension 9 is provided on one end of the game board 10 so that it may project over the back of the folded game board. This extension 9 may be secured to the back of the game board by an ordinary snap fastener 12, and a foldable gripping flange 13 may be provided on the extension to facilitate the manipulation thereof.

40 In this modification I have illustrated a slightly different form of framing device 14 which has its bar 15 connecting the sides of the framing device.

I would have it distinctly understood that the invention is not limited to the exact manner of forming or shaping the framing device, as this may be made in various ways. The broad idea is to provide a framing device of such shape and construction that it will act to hold flat game pieces in assemblage, so that when the framing device is moved or removed the pieces will be on the board.

In the modification illustrated in Figures 8, 9, and 10, one end of the game board 21 is permanently secured over one side of the framing device 16, a portion of said framing device being preferably thicker than the other portion, and the edge of the material of the game board co-operating with a recess 17 in the framing device constituting a groove in which the other end of the game board may be positioned, as shown in Figure 10, so as to hold the parts assembled. A finger gripping tab 18 may be provided on the end of the game board to facilitate the manipulation thereof.

The modification illustrated in Figure 11 is similar to the preferred form with the exception that the framing device 19 is so connected to one end of the board 20 as to be hingedly connected.

I have illustrated a number of different forms of my improved game apparatus, all of which include the broad idea of a movable framing device adapted to be enclosed within a folding game board and to hold flat game pieces with their faces visibly exposed so that the game pieces lie on the plane surface of the board ready for play as soon as the game board is opened, and I desire to cover this idea broadly. 80

I use the term "framing device" in its broadest possible sense to include a device which actually frames the set of game pieces and which permits the operation or manipulation as above set forth.

Various slight changes and alterations might be made in the general form of the parts described without departing from the spirit of the invention, and hence I do not limit myself to the precise details set forth but consider myself at liberty to make such slight changes and alterations as fairly fall within the spirit and scope of the appended claims. 90

I claim:

1. A game apparatus, including a folding game board, and a framing device adapted to hold flat game pieces located on one section of the game board, and said framing device enclosed and covered at opposite sides when the game board is folded thereon. 100

2. A game apparatus including a folding game board, a set of flat game pieces adapted to be positioned on the board, a framing device adapted to hold said game pieces in an assemblage on one section of the game board, and said game board when folded adapted to cover both the lower and upper faces of the framing device and the game pieces. 105 110

3. A game apparatus including a game board, a framing device adapted to rest on a section of the game board, and providing space therein for the accommodation of flat game pieces, said game board having a pair of spaced parallel fold lines approximating the thickness of the game pieces and the framing device, whereby when the game board is folded onto the framing device and the game pieces the board will act as a cover for both faces of the framing device and game pieces. 115 120

4. A game device including a game board, a framing device adapted to rest on a section of the game board, and providing space therein for the accommodation of flat game pieces, said game board having a pair of spaced parallel fold lines approximating the thickness of the game pieces and the framing device, whereby when the game board

is folded onto the framing device and the game pieces the board will act as a cover for both faces of the framing device and game pieces, and means for holding the parts in folded position.

5. A game apparatus including a game board, a framing device adapted to rest on a section of the game board, and providing space therein for the accommodation of flat game pieces, said game board having a pair

of spaced parallel fold lines approximating the thickness of the game pieces and the framing device, whereby when the game board is folded onto the framing device and the game pieces the board will act as a cover for both faces of the framing device and the game pieces, and an envelope into which said folded framing device and game pieces are adapted to slide. 15

DAVID REISZ.
